UNITED STATES PATENT OFFICE.

LEANDER W. HAMMOND, OF PLAINFIELD, NEW JERSEY, ASSIGNOR OF ONE-HALF TO SAMUEL A. WALLACE, OF NORTH PLAINFIELD, NEW JERSEY.

PROPELLER-WHEEL.

SPECIFICATION forming part of Letters Patent No. 695,389, dated March 11, 1902.

Application filed September 21, 1901. Serial No. 76,050. (Model.)

To all whom it may concern:

Be it known that I, LEANDER W. HAMMOND, a citizen of the United States, residing at North Plainfield, in the county of Somerset and State of New Jersey, have invented new and useful Improvements in Propeller-Wheels, of which the following is a specification.

My invention relates to propeller-wheels, and has for its object to construct a device in which great propulsive power is attained with a small resistance.

With this object in view my invention consists in the construction, arrangement, and combination of parts, as will be first fully described in the specification and then claimed.

In the drawings forming a part of this specification, and in which like symbols of reference represent corresponding parts in the several views, Figure 1 is a perspective of the device. Fig. 2 is a side elevation of the hub-sections. Fig. 3 is a detail of one of the paddles.

The numeral 1 designates the hub of my propeller, which comprises two funnel-shaped or approximately conical sections 2 and 3, placed base to base.

The hub 1 is apertured longitudinally to accommodate a propeller-shaft 5. The hub 1 is traversed by three diagonally extending grooves 4, corresponding to the number of blades 6 employed in constructing the propeller. The grooves 4 are beveled on one side and perpendicular on the other, forming square shoulders 4^a.

The blades 6 each have an apertured disk 6^a integral therewith. The blades 6 are not plane, but are twisted or turned through an angle to the plane of the disk 6^a, which angle is equal to the pitch of the screw. The blades

6 are secured by clamping the disks 6^a between the hub-sections 2 and 3.

Mounted on the ends of the blades 6 are members 7, having oppositely-extending flanges designed to confine the water and prevent its escaping over the ends of the blades.

In operation the shaft 5 is revolved and the section 3, aided by the shoulders 4^a of the hub, will bore through the water like a gimlet and throw the water outwardly toward the blades 6, thereby preventing dead water in front of the screw. The blades 6 will engage the water and force the boat along. The flanges on the members 7 will prevent the escape of water over the ends and reduce the slipping of the screw to a minimum. The rear portion 2 of the hub will fill the void or vacuum which always forms back of the screw and lessens its grip. The gimlet-like action will also assist in propelling the boat.

I do not wish to be limited as to details of construction, as these may be modified in many particulars without departing from the spirit of my invention.

Having fully described my invention, what I claim as new, and desire to secure by Letters Patent, is—

In a propeller, the combination of a hub coned off at both ends and having diagonal grooves therein, and blades mounted on said hub, substantially as described.

In testimony whereof I have hereunto set my hand in presence of two subscribing witnesses.

LEANDER W. HAMMOND.
